Des. 202,071
Patented Aug. 24, 1965

202,071

PAIR OF SUNGLASSES

Jack N. Simpson, Reading, Pa., assignor to The Electric Storage Battery Company, Philadelphia, Pa.

Filed May 18, 1964, Ser. No. 80,019

Term of patent 14 years

(Cl. D57—1)

Fig.1.

Fig.2.

Fig.3.

FIG. 1 is a bottom view of a pair of sunglasses, showing my new design;

FIG. 2 is a front view, and FIG. 3 is a side, perspective view thereof taken from the left of FIG. 2.

I claim:

The ornamental design for a pair of sunglasses, substantially as shown.
